[57] CLAIM

The ornamental design for a combined toothbrush head and handle unit and cover therefor, as shown and described.

DESCRIPTION

FIG. 1 is a front elevational view of a combined toothbrush head and handle unit and cover therefor showing our new design with the head and handle unit being enclosed in the cover, the rear being a mirror image; FIG. 2 is a left end elevational view thereof; FIG. 3 is a right end elevational view thereof; FIG. 4 is an exploded front elevational view thereof; FIG. 5 is a left end elevational view of the cover shown separately for clarity of illustration only; FIG. 6 is a longitudinal cross-sectional view of the cover of FIG. 4; FIG. 7 is a front elevational view of FIG. 1, shown assembled for use; FIG. 8 is a top plan view of the head and handle unit shown separately for clarity of illustration only, the bottom plan being unornamented; FIG. 9 is a left end elevational view thereof; and, FIG. 10 is a right end elevational view thereof.
